SANITARY BED PAN CONTAINER

Charles W. Beamer, Mojave, Calif.

Application November 23, 1937, Serial No. 176,130

2 Claims. (Cl. 4—222)

This invention appertains to new and useful improvements in hospital supplies and more particularly to a container in which bed pans can be carried in a sanitary and convenient manner.

5 The principal object of the present invention is to provide a container in which one or more bed pans can be carried, especially in hospitals by nurses and orderlies, without any inconvenience to the handlers.

10 Another important object of the invention is to provide a bed pan carrier in which bed pans can be conveniently carried and wherein means is provided for deodorizing the contents of the bed pan or pans within the container.

15 These and various other important objects and advantages of the invention will become apparent to the reader of the following specification.

In the drawings:—

Figure 1 represents a side elevational view of 20 a single bed pan type of container.

Figure 2 is a side elevational view of a double bed pan carrier.

Figure 3 is a top plan view of the structure shown in Figure 1.

25 Figure 4 is an enlarged vertical sectional view taken substantially on the line 4—4 of Figure 1.

Figure 5 is a fragmentary side elevational view of the valve element.

Referring to the drawings wherein like numerals designate like parts, it can be seen that the device consists of an elongated box-like structure 5 of aluminum or some other suitable light weight material, one end of which is provided with the hinged closure 6 while the other end, that is, in a single type of container, is preferably rounded off as at 7.

The top of the shell 5 is provided with the handle 8 and adjacent this is the deodorant dispenser generally referred to by numeral 9. This dispenser consists in the provision of an internally threaded neck 10 on the top of the shell 5 into which the lower portion of the barrel 11 is threadedly disposed as at 12. The barrel 11 is provided with the horizontally disposed partition 13 about midway between its ends and this is provided centrally with an opening from the edge portion of which rises and descends the cylinder 14 within which moves the plunger 15, which plunger 15 is slidably disposed through a packer 16 or packing gland 16 and is provided with a hand knob 17 at its upper end. The packing gland 16 is provided in the cap 18 which is threadedly disposed over the upper end of the barrel 11 and has the filler plug 19 therein.

55 The cylinder 14 is provided with ports 20

above the partition 13. Depending from the plunger 15 is the stem 21 of the valve element 22 which stem has the cross pin 23 therein above the valve seating block 24 and between this pin 23 and the block 24 is interposed the coiled compressible spring 25 which serves to maintain the valve element 22 normally engaged against the seat surface 26 of the seating block 24 so that none of the deodorant from either of the two cells 27—28 can escape.

10 It can now be seen, that by lifting the latch 29, the closure 6 can be released so that a bed pan can be inserted into the shell 5. The handler can now press downwardly on the plunger 15 and the shoulder 30 will move downwardly as 15 the valve 22 becomes unseated to position itself below the ports 20. All of the contents of the cell 27 will now dispense into the bed pan for deodorizing the contents thereof. Should the nurse or orderly have two bed pans to be carried, and 20 the double type of carrier shown in Figure 2 is being employed, the first pan can be inserted in the upper compartment of the carrier generally referred to by numeral 31 (see Figure 2) whereupon the dispenser 9 can be operated for discharging the contents of the lower cell 27 into 25 the bed pan, after which the bed pan can be removed from the upper compartment and inserted into the lower compartment, followed by the placing into the upper compartment of the 30 second bed pan. Obviously, when the plunger 15 has been released after the discharge of the contents of the cell 27, the plunger 15 will be returned to the position shown in Figure 4 allowing the liquid content of the upper cell 28 to 35 pass through the ports 20 and into the lower cell 27, so that when the dispenser is operated the second time for deodorizing the contents of the second pan the lower cell will be filled and immediately discharged into the said second bed pan upon opening of the valve 22.

40 While the foregoing specification sets forth the invention in specific terms, it is to be understood that numerous changes in the shape, size and materials may be resorted to without departing 45 from the spirit and scope of the invention as claimed hereinafter.

Having described the invention what is claimed as new is:—

1. A bed pan carrier comprising a shell-like 50 structure defining a compartment for the reception of a bed pan, said shell-like structure having a horizontal partition dividing the interior thereof into a pair of compartments capable of receiving a pair of bed pans, and a de- 55

odorant dispenser mounted on the shell-like structure and having a plurality of deodorant material containing cells therein.

2. A bed pan carrier comprising a shell-like structure defining a compartment for the reception of a bed pan, said shell-like structure having a horizontal partition dividing the interior

thereof into a pair of compartments capable of receiving a pair of bed pans, and a deodorant dispenser mounted on the shell-like structure and having a plurality of deodorant material containing cells therein, and means for dispensing 5 the said cells successively.

CHARLES W. BEAMER.
